UNITED STATES PATENT OFFICE.

ISIDOR ABRAHAMS, OF CINCINNATI, OHIO.

TROUSERS-POCKET

1,036,054.

Specification of Letters Patent. Patented Aug. 20, 1912.

Application filed February 28, 1910. Serial No. 545,330.

To all whom it may concern:

Be it known that I, ISIDOR ABRAHAMS, a citizen of the United States, residing at Cincinnati, in the county of Hamilton and State 5 of Ohio, have invented certain new and useful Improvements in Trousers-Pockets, of which the following is a specification.

My invention relates to a trousers pocket and has for its object the constructing and 10 arranging of the pocket so as to guard the contents of the same and reduce the likelihood of loss from the pocket of its contents, and especially of small objects, such as loose change and the like.

15 My invention consists in providing facings at the respective sides of the pocket-opening or mouth which are connected to the sides of said pocket-opening at their outer edges and extend inwardly to substantial 20 extent into the pocket at the respective sides thereof for forming auxiliary pouches, between said facings and the respective walls of said pocket, the inner forward edges of said facings being in open relation between 25 their ends, for permitting communication across said edges with said auxiliary pouches, which latter open inwardly and forwardly, and further in attaching the lower ends of the pocket-facings to the 30 pocket for forming a lower pouch-extension for the pocket under said facings; and the invention will be further readily understood from the following description and claims, and from the drawings, in which latter:

35 Figure 1 is a side elevation of so much of a trousers garment as is necessary to illustrate my invention, having my invention applied thereto and partly broken away for better illustration of the parts. Fig. 2 is an 40 inside elevation of the same, partly broken away. Fig. 3 is a cross-section on the line 3—3 of Fig. 2; and Fig. 4 is a detail in cross-section on the line 4—4 of Fig. 2.

1 represents so much of the trousers as is 45 necessary to illustrate my invention.

2 is the pocket, and 3 the side seam of the trousers.

4 is the pocket opening.

5 and 6 are facings at the pocket-opening 50 which are respectively secured to the sides 7 8 of the pocket-opening at their outer longitudinal edges, as by the seams 3 and 10, and extend inwardly to substantial extent into the pocket.

55 The inner side wall of the pocket is indicated at 11 and the outer side wall thereof

is indicated at 12. The upper end of the pocket is closed preferably by the usual band seam 13.

The upper ends of the facings are preferably connected by a seam 14 which slants downwardly into the inside of the pocket, and the lower ends of the facings are connected preferably by a seam 15, extending downwardly into the inside of the pocket. 65 This construction causes the facings to extend downwardly and inwardly into the pocket for convenience of the wearer in inserting and withdrawing his hand. The inner longitudinal forward edges of said facings between their ends are free of attachment to the side walls of the pocket. These forward edges extend up and down. The inner upper corner of the connected facings is secured preferably to but one of the walls 70 of the pocket, as the outer wall 12, by means of stitching 16, thereby leaving the upper ends of the facings between the stitching 16 and the outer edges of the facings free of attachment to the wall of the pocket, as 75 shown at 16', for the purposes hereinafter described.

The lower ends of the facings are preferably connected to one of the walls of the pocket, preferably the outer wall, which 80 may be also accomplished by the seam 15. There may be a seam 17 which connects the walls of the pocket in rear of the seam 15, the seam 17 being located between the lower ends of the facings and the rear edge 18 of 85 the pocket, the seam 17 being in effect a continuation of the seam 15. The rear portion of the pocket above said seam 17 may be closed by a seam 19 substantially coincident in position with the side seam 3. The upper and lower ends of the pocket-opening 90 may be reinforced by tacks 20 21. The side facings 5 6 extend inwardly to substantial extent into the pocket, and auxiliary pouches 22 23 which open forwardly are 95 thereby formed between said respective facings and the side walls of the pocket, and a lower pouch-extension 24 is formed in the lower portion of the pocket under the connected facings. If now the wearer is in a 100 sitting or reclining position, with the bottom of the pocket elevated above the pocket-opening, or the trousers are hung in position with the pocket up-side down, the tendency will be for any loose objects in the 105 pocket, such as small change and the like, to be lodged in the auxiliary pouches between

the facings and the walls of the pocket, and be thereby prevented from escaping through the opening of the pocket. The attachment of the upper and lower ends of the facings to the wall of the pocket insures that the inner or forward ends of the facings will be held sufficiently forward rigid to prevent collapse of the facings, the inner edges of the facings however naturally assuming a 10 location slightly distanced from the walls of the pocket when the pocket is in other than a depending position; so that the contents of the pocket readily find lodgment in said auxiliary pouches.

15 When the pocket is again in upright position, any objects which may have been received in said auxiliary pouches or in the top of the pocket will naturally fall to the bottom of the pocket, and the stitching 16 and seam 15, preferably slanting forwardly, naturally direct said objects toward the bottom of the pocket. The upper ends of the facings between the stitching 16 and the outer edges of the facings being free of attachment to the wall of the pocket permits any objects which may be lodged in the extreme upper corner of the pocket to pass between the unattached portion of said facings and the wall of the pocket and through 30 one of the auxiliary pouches to the bottom of the pocket.

The stitching 15 secures the lower ends of the said facings preferably to the front wall of the pocket so that the tendency will be 35 for the contents of the pocket to bulge the pocket backward or toward the person of the wearer and thereby avoid a bulging appearance at the pocket position of the trousers.

40 The unintentional removal of objects from the pocket is also made difficult by the extension of the connected lower ends of said facings into the interior of the pocket for forming the lower pouch extension 24.

45 Having thus fully described my invention, what I claim as new and desire to secure by Letters Patent is:

1. In combination, a trousers pocket having an outer opening extending up and

down, and facings therefor, the said facings 50 extending up and down and having rear edges and front edges extending up and down in the general direction in which said outer opening extends, the said rear edges being secured lengthwise up and down at 55 the respective sides of said pocket-opening, and the said front edges being independently flexible and being free of attachment to each other intermediate of their ends, the upper and lower ends of said facings 60 being respectively connected together and connected to the wall of said pocket for forming forwardly opening auxiliary pouches at the sides of said facings, the said connection of the wall of said pocket at 65 the lower ends of said facings extending rearwardly along the lower edges of said facings for forming a lower pouch extension in the lower end of said pocket below said auxiliary pouches, and said lower pouch 70 extension opening forwardly, substantially as described.

2. In combination, a trousers pocket and facings for the respective walls of said pocket, said facings being attached at their 75 rear longitudinal edges to the respective sides of the pocket-opening and extending inwardly into said pocket, the upper and lower ends of said facings being respectively connected by seams extending down, 80 wardly and forwardly, the respective ends of said connected facings being secured to said pocket, and the forward longitudinal edges of said facings intermediate of their ends being free of attachment to each other 85 and to the walls of said pocket, and constructed and arranged for forming auxiliary pockets extending up and down lengthwise of said pocket-opening, substantially as described. 90

In testimony whereof, I have signed my name hereto in the presence of two subscribing witnesses:

ISIDOR ABRAHAMS.
